DESIGN FOR A BOWL FOR LIGHTING FIXTURES

Thomas W. Rolph, Newark, Ohio, assignor to
Holophane Company, Inc., New York, N. Y., a
corporation of Delaware

Application October 5, 1940, Serial No. 95,662

Term of patent 14 years

To all whom it may concern:

Be it known that I, Thomas W. Rolph, a citizen of the United States of America and a resident of Newark, in the county of Licking and State of Ohio, have invented a new, original, and ornamental Design for a Bowl for Lighting Fixtures, of which the following is a specification, reference being had to the accompanying drawing, forming a part thereof.

The single figure in the drawing is a perspective view of the bowl for lighting fixtures showing my new design.

I claim:

The ornamental design for a bowl for lighting fixtures, as shown.

THOMAS W. ROLPH.
